GOLF CLUB HEAD

Walter J. Handzlik, Jr., Detroit, Mich., assignor to Lyon Incorporated, Detroit, Mich., a corporation of Delaware

Application October 15, 1957, Serial No. 48,102

Term of patent 14 years

(Cl. D34—5)

Fig. 1

Fig. 2

The dotted lines in Figures 2 and 3 showing the conventional club shaft are for illustrative purposes only.

I claim:

The ornamental design for a golf club head, substantially as shown and described.
